(57) **CLAIM**

The ornamental design for a slip leash, as shown and described.

DESCRIPTION

FIG. 1 is a front perspective view of a slip leash, showing my new design;

FIG. 2 is a partial right side elevation view, with the left side being a mirror image thereof;

FIG. 3 is a cross-section view taken along line 3-3 in FIG. 2;

FIG. 4 is a cross-section view taken along line 4-4 in FIG. 2;

FIG. 5 is a top plan view of the slip leash shown in FIG. 1; FIG. 6 is a left side elevation view of the slip leash; and, FIG. 7 is a rear perspective view of the slip leash, shown within an environment of use.

The broken lines represent portions of the slip leash that form no part of the claimed design. In FIG. 7, the broken lines depicting a dog represent environmental subject matter that forms no part of the claimed design.

In FIGS. 1 and 5, the slip leash is shown broken away for ease of disclosure on the drawing sheet.
